UNITED STATES PATENT OFFICE.

BENJAMIN E. GETZ, OF MORTON, ILLINOIS, ASSIGNOR, BY MESNE ASSIGNMENTS, OF ONE-HALF TO GETZ POWER WASHER CO., OF MORTON, ILLINOIS, A CORPORATION OF ILLINOIS, AND ONE-HALF TO WESTINGHOUSE ELECTRIC & MANUFACTURING COMPANY, OF EAST PITTSBURGH, PENNSYLVANIA, A CORPORATION OF PENNSYLVANIA.

WASHING MACHINE.

Application filed April 14, 1923. Serial No. 631,965.

This invention has reference to washing machines, and particularly to that type including a clothes container or tub which is mounted for movement in the frame of the machine. 5 In its preferred form the container or tub is oscillated, but to those skilled in this art it will be understood that the movement of the operating means could be extended so as to impart an alternating rotary movement to 10 the container or tub, so as to rotate it approximately a full revolution before reversing its operation, instead of a partial rotation, as herein shown.

The invention has for its principal object 15 to provide a controllable means for the tub moving means; such controllable means movable to different positions and adapted in one of its positions to impart movement to the tub and in another of its positions 20 adapted to restore the tub to normal stopped position, without stopping the movement of the tub moving means.

The invention has for a further object to 25 provide a controllable means for the tub moving means which is adapted to give to the tub a variable movement, such movement being under the full control of an attendant and being dependent on the position to which the controllable means is 30 adjusted. In one position of the controllable means movement may be imparted to the tub, in another position of the controllable means the tub is restored to its normal stopped position, a variable movement being 35 imparted to the tub as the controllable means is moved or held between such two described positions.

The invention herein described and shown 40 is an improvement on the generic idea disclosed in the application of Thomas Litwiller and John Leader bearing Serial No. 442, 336 (Letters Patent No. 1,460,203 dated June 26, 1923), and as to such generic disclosure a disclaimer is here made.

45 The present improvement resides in the controllable means, and in the inclusion of means for holding the controllable means in selective positions between its two extreme movements, whereby variable movements 50 may be imparted to the tub, at the will of the attendant or operator.

That the invention may be more fully understood, reference is had to the accom-

panying drawings, forming part of the description, and illustrating a preferred embodiment of the invention, in which:—

55 Figure 1 is a side elevation of my controllable means for washing machines, and operating connections between the same and a power means, the tub being shown in dotted lines in different positions, and dotted lines illustrating the oscillation of the tub;

60 Figure 2 is a view somewhat similar to Figure 1, except that the controllable means has been moved from an operative to an inoperative position and the tub brought to 65 normal position and stopped, without stopping the operating means, and

65 Figure 3 is a detail showing a means 70 which is employed to stop and hold the controllable means at different points between the extreme and predetermined points to which the controllable means may be moved, whereby variable movement of the tub is obtained.

75 Like characters of reference denote corresponding parts throughout the figures.

The frame structure which may be of any suitable character, is only partly shown and then only in dotted lines; likewise the clothes container may be of any suitable design and so much of it that is shown is illustrated by dotted lines, full lines being employed to show the tub moving means and controllable means, certain positions of 85 which, however, are illustrated by dotted lines.

The frame of the machine includes a base member 1, and side members 2, only one of 90 which is illustrated, and a top or cover member 3. Such frame, if desired, like many present day machines may also have a cabinet or enclosing casing, not shown. As a supporting means for the container or tub 4, a frame 5 is provided in which trunnions 6 95 or other journal means may have a bearing, whereby the container or tub may have movement. In the present disclosure this movement is preferably oscillatory. The container or tub would naturally include an opening, not shown, through which clothing or other materials would be inserted into and withdrawn therefrom, and such opening covered or closed, when desired, by a suitable lid 100 or cover, not shown.

105 In Figure 2, the container or tub has been

restored to its normal position, or as some would say returned to its neutral position, and stopped, the operating means continuing in operation, and the controllable means 5 idling and without movement being imparted to the container or tub. In Figure 1 the controllable means has been moved to a position which will cause the operating means to impart movement through the controllable 10 means to the tub, and as a result the tub is oscillated back and forth, somewhat as indicated by the dotted line positions of the tub.

By "normal" or "neutral" position of the tub, it is to be understood that that is the 15 position the tub occupies when it is stopped so that the lid or cover thereof may be removed by an attendant to permit the removal of clothes or fabrics from the tub and the placing of other articles or materials 20 therein. Also, by the use of the word "restore" I mean bringing back or righting of the tub to "normal" or "neutral" position at the same time that the operating means is made ineffective so far as operating the tub 25 is concerned, yet without disturbing the movement of the operating means.

By the use of a mechanism such as I employ and which I am about to describe, the 30 use of spring constraining means for returning the tub to its normal position and for balancing the tub, are unnecessary and entirely done away with, and yet the attendant need have no concern about the tub being restored to normal position, as such is the 35 natural result when the controllable means is moved to discontinue the movement of the tub.

7 designates a driving shaft, which may 40 form a part of or be included in any suitable transmission, not shown, thru which power is imparted to said shaft from the usual motor, not shown. To one end of said shaft is connected a crank-arm 8.

9 designates a pivot member which is pref- 45 erably supported by being connected to one side of the container or tub 4, and in spaced relation to the axial center of the tub. On said pivot member is carried a casting 10, forming a bearing member and being formed 50 with a barrel or sleeve-like part 11 and a chambered portion 12. Slidably carried through said barrel or sleeve-like part of said member 10 is a rod or bar 13, its inner end connected with a casting 14 having connected thereto a pivot member 15 to which is connected a lever 16 fulcrumed at 17 to the frame 5. The outer end of the rod or bar 13 has connected thereto a casting 18 having a shank 19 which is pivotally connected with the upper end of a pitman or connecting bar 20, which is connected at its lower end to the crank-arm 8.

The rod or bar 13 is provided with a plurality of spaced seats or depressions 21 with 55 which coat the ball member 22 located in

the casting 10 at the lower end of the chamber 12 in which is carried the spring 23 to normally hold the ball member in contact with the rod or bar 13. As the rod or bar 13 is moved back and forth through the casting 10 the ball member 22 will ride or roll on the surface of said rod or bar, and enter into each seat or depression 21 brought coincident therewith. The lock formed by the ball and seats or depressions to hold the rod or bar in different positions, whereby a variable movement may be imparted to the tub, may be felt out by the attendant during the movement of said rod or bar, and very little effort or exertion on the part of the attendant will be required to release the rod or bar and to move it to its two extreme and predetermined positions, one operative and the other inoperative.

When the parts are in operative position 85 the member 15 is in axial coincidence with the axis of the container or tub 4, the rod or bar 13 having been moved inwardly bringing the casting on the outer end thereof adjacent the casting 10 on the pivot member 9. In 90 such position of the parts, the rod or bar 13 may be oscillated up and down around the pivot pin 15, as the connecting or pitman bar 20 is moved up and down, due to the rotation of the crank-arm 8; the thrust of said 95 bar 20 being substantially in the direction of the pivot member 9 on the tub and moving the tub on its axis, somewhat in the manner shown in Figure 1. When the parts are in inoperative position, that is so far as the 100 movement of the tub is concerned, the pivot member 15 is in axial coincidence with the pivot member 9 and the casting 14 on the inner end of the rod of bar 13 has been moved to a position adjacent the casting 10. 105 In this position of the parts as the connecting or pitman bar 20 is moved up and down the rod or bar 13 will be oscillated but will idle on the pivot member 15, somewhat in the manner shown in Figure 2, and without 110 imparting movement to the tub. The movement of the lever 16 which will bring the member 15 into axial coincidence with the member 9 automatically restores the tub to the "normal" or "neutral" position seen in 115 Figure 2.

In addition to the advantage of restoring the tub to normal or neutral position and stopping its movement, my improved mechanism has the further advantage of permitting the attendant to move the controlling means to different selective positions between its two extreme and predetermined positions, whereby greater or less oscillation of the tub may be obtained. This is 120 particularly desirable in the handling of coarse and fine fabrics and clothing. With such a controllable means as I have disclosed the movement of the tub may be gradually 125 started and gradually stopped and there is 130

no jerking or jiggling of the tub as it is brought to a positive stop.

What I claim is:—

1. In a machine of the character described, in combination, a tub mounted for oscillation, a sleeve like member connected to said tub, a rod having a slidable relation in said member, a lever having connection with one end of said rod for moving the latter alternately to operative and inoperative positions, and during such movement to the latter position bringing the tub to its normal position, an operating mechanism, and operating connections between said rod and said mechanism.
2. In a machine of the character described, in combination, a tub mounted for oscillation, a sleeve like member connected to said tub, a rod having a slidable relation in said member, a lever having connection with one end of said rod for moving the latter alternately to operative and inoperative positions, and during such movement to the latter position bringing the tub to its normal position independently of the amplitude of oscillations of said tub, an operating mechanism, and operating connections between said rod and said mechanism.
3. In a machine of the character described, in combination, a frame, a tub mounted for oscillation in said frame, and operating means for the tub comprising a pivot member arranged in spaced relation to the axial center of the tub, a sleeve like member on said pivot member, a pivotally sup-

ported rod having a slidable relation in said sleeve like member, and means for moving the axis of the pivot for said rod alternately into axial coincidence with the axis of the tub and the axis of said pivot member.

4. In a machine of the character described, in combination, a frame, a tub mounted for oscillation in said frame, and operating means for the tub comprising a pivot member arranged in spaced relation to the axial center of the tub, a sleeve like member on said pivot member, a pivotally supported rod having a slidable relation in said sleeve like member, and means for moving the axis of the pivot for said rod alternately into axial coincidence with the axis of the tub and the axis of said pivot member without stopping the movement of said operating means.

5. In a machine of the character described, in combination, a tub mounted for movement, a member connected to the tub, a rod slidably carried through said member and provided with a plurality of spaced indentations, a lever, a member on one end of the rod in pivotal connection with said lever, the axis of which is adapted to be moved alternately into axial coincidence with the axis of the tub and the member connected thereto, means to oscillate said rod, and means to engage in the indentations in said rod to hold the rod in different positions.

In witness whereof, I have hereunto affixed my hand this 11th day of April, 1923.

BENJAMIN E. GETZ.
